UNITED STATES PATENT OFFICE.

CORA M. THOMPSON, OF LELAND, ILLINOIS.

ATTACHMENT FOR BROOMS.

No. 800,886.

Specification of Letters Patent.

Patented Oct. 3, 1905.

Application filed August 29, 1904. Serial No. 222,630.

To all whom it may concern:

Be it known that I, CORA M. THOMPSON, a citizen of the United States, residing at Leland, in the county of LaSalle and State of Illinois, have invented certain new and useful Improvements in Attachments for Brooms, of which the following is a specification, reference being had to the accompanying drawings.

My invention relates to attachment for brooms; and its object is to provide new and improved means by which a scrubbing-cloth or protecting-cloth may be readily and conveniently fastened over brooms and which may be readily disengaged, so that the broom may be used in its ordinary way. As is well known, it is frequently desirable in using a broom for scrubbing or mopping certain kinds of floors or for certain work in which it is not desirable to use the broom itself that a piece of cloth or other suitable material be fastened over the broom for that purpose. It may also frequently be desirable, to protect the broom, to cover it with cloth or similar material, which may be readily removed when occasion demands. It is the object of my invention to provide a new and improved device for securing such cloth on the broom.

In the drawings, Figure 1 is an isometric view of my device. Fig. 2 is an enlarged detail of the hinged end of my device, showing the spring by which it is normally held open; and Fig. 3 shows my device applied to a broom.

Referring to the drawings, 4 5 indicate two side frames preferably formed of wire bent 35 into the form substantially of a long rectangle, as is shown in Fig. 1. These two side frames are hinged together at one end by a hinge 6. The length of the hinge 6 is such that when the two side frames are clasped 40 upon the broom in the manner hereinafter described they will have to be pressed together firmly against the broom, which will tend to force them outward when clasped, so that, as hereinafter described, they may be held firmly 45 in place.

7 indicates a latch which is preferably formed of spring metal and which is hinged at one end to the side frame 5 and is provided at the other end with a bent-over portion 8, which is adapted to spring over and

engage the free end of the other side piece 4, so as to clasp the device firmly upon the broom.

9 indicates a series of projecting points which are adapted to pierce the cloth or other similar material with which the broom is covered and to enter sufficiently deeply between the fibers of the broom to secure the cloth in place. These points are preferably formed upon two ends of a piece of wire, which, as shown in Fig. 1, is coiled near its middle 60 around one arm of each side piece and outer ends are coiled around the other arm, so as to leave the pointed ends projecting inwardly a suitable distance. They may, however, be fastened in any other approved way. 65

10 indicates a spring which is applied to the hinged end of the device and is adapted to normally hold the two side pieces apart, as is shown in Fig. 2. This spring, as shown in Fig. 2, is preferably formed of two pieces of 70 spring-wire twisted together near their central portions and having their free ends extending around the hinge and embracing the two side frames.

Fig. 3, as was said above, shows the manner in which the device is applied to a broom. The cloth or other suitable material with which it is desired to cover the broom is placed upon the broom. The appliance is then placed around the cloth and the open ends pressed 80 together and latched by the latch 7. The points 9 will therefore project through the cloth and into the fibers of the broom, and together with the pressure exerted upon the device by its being clasped tightly around the 85 broom the spring will hold the latch firmly in place and the covering upon the broom.

That which I claim as my invention, and desire to secure by Letters Patent, is—

1. In an attachment for brooms, the combination with two side members, of a hinge member hinging the side members together at one end, a clasp member at the other end adapted to secure the side members upon the broom, a plurality of inward-projecting points, and 90 a spring adapted to normally hold said members in their open position, substantially as described.

2. An attachment for securing covering to brooms, consisting of two side members each 100

composed of wire bent to form two side and two end portions, wires bent around the side portions of said side members and having their free ends pointed to enter the fibers of the 5 broom, a hinge member connecting the end portions of the side members at one end, and a clasp member adapted to clasp the end por-

tions of the side members at the other end upon the broom, substantially as described.
